United States Patent Office.

JOHN R. WILBUR, OF CHICOPEE, MASSACHUSETTS.

Letters Patent No. 74,965, dated February 25, 1868.

IMPROVEMENT IN CORN-SHELLERS.

The Schedule referred to in these Letters Patent and making part of the same.

TO ALL WHOM IT MAY CONCERN:

Be it known that I, JOHN R. WILBUR, of Chicopee, in the county of Hampden, and State of Massachusetts, have invented a new and improved Machine for Shelling Corn; and I do hereby declare the following to be a full and exact description thereof, reference being had to the accompanying drawings, and to the letters of reference marked thereon, in which—

Figure 1 is a perspective view of my machine, and

Figure 2 is a sectional view of the under side of the bonnet.

In the construction of my cylinder, which is made of cast metal, it may be cast with the ribs and points on the cylinder or in the bonnet, or they may be put on the cylinder after it is cast plain, and may be made of iron or steel, and attached in any ordinary manner to the cylinder. In fig. 1, A', the frame; A, the cylinder; B, the bonnet; C C, the weights, attached to cords passing over pulleys, and are fastened to the lower part of the bonnet, to hold it down on the cylinder when shelling corn; D, the hopper, through which the corn is fed to the cylinder and bonnet; E, the vibrating-arm, attached to the side of the frame and to the hopper D, and by which means a reciprocating motion is given to the hopper, to assist in feeding down to the cylinder; F, the point at which the cords are attached to the bonnet B; H, the crank, attached to the shaft or arm E; K K K, the ribs on the cylinder A; L, the points or teeth in their relative positions. It will be seen that I construct the ribs of a V-shape, made in sections. These ribs are placed on the cylinder, with the point of the V in the direction the cylinder revolves in shelling the corn. The point is set about the middle of the cylinder, and then points out to the periphery of the same. Other ribs of V-shape are set on the cylinder, each succeeding one being about half an inch shorter, until the given section, say four inches, or in accordance to the size of the cylinder and the number of sections I may design to use. The open or wide end of these V ribs, all in each section, terminate in a line at right angles on the periphery of the cylinder. Thus section after section, constructed in like manner, is put on, until the outer periphery of the cylinder is covered with these V-shaped ribs in alternate-sections, all having the sharp point of the V in the direction the cylinder is to revolve when in use. The points or teeth L are set on in rows at given spaces, viz, at the base or wide ends of the ribs V-shaped, directly at right angles to the cylinder, and are regularly interspersed over the face of the cylinder, as seen in figs. 1 and 2.

In the operation of my invention, motion is given to the cylinder by the crank, or any other power may be applied, the corn being put into the hopper. As the cylinder is made to revolve by means of the crank H and arm or shaft E; the hopper is made to oscillate, thus feeding the corn down on to the cylinder, and under the bonnet (the bonnet being pressed up tightly against it by means of weights C C) giving to it an elastic motion. As the ears are pressed forward by the teeth L, the sharp edges of the ribs sink between rows or kernels of the corn, while the V-form of the ribs gives a lateral motion which rends the seed from the ear or cob, and the same forms of ribs and teeth on the under side of the bonnet greatly facilitate the operation of shelling.

Having thus described the nature of my invention, I do not broadly claim ribs on a cylinder, as this is not new; nor do I claim diamond-shaped ribs or toothed bonnets, or the combination of both, as described by Edwin F. Sherman, in his application for improvements in corn-shellers now pending in the Patent Office; but

What I do claim, and desire to secure by Letters Patent, is—

1. The V-shaped ribs K, in combination with teeth or points L on the face of the cylinder A and bonnet B, constructed substantially as described, and for the purposes set forth.
2. I claim the crank H and shaft or arm E, in combination with the hopper D, constructed as described, and for the purposes set forth.

JOHN R. WILBUR.
